(57) **CLAIM**

We claim the ornamental design for a blender jar, as shown
and described.

DESCRIPTION

FIG. 1 is a first side perspective view of a blender jar of the
present disclosure;

FIG. 2 is a second side perspective view of the blender jar
of FIG. 1;

FIG. 3 is a front perspective view of the blender jar of FIG.
1;

FIG. 4 is a rear perspective view of the blender jar of FIG.
1;

FIG. 5 is a first side elevational view of the blender jar of
FIG. 1;

FIG. 6 is a second side elevational view of the blender jar of
FIG. 1;

FIG. 7 is a third side elevational view of the blender jar of
FIG. 1;

FIG. 8 is a fourth side elevational view of the blender jar of
FIG. 1;

FIG. 9 is a top plan view of the blender jar of FIG. 1; and,
FIG. 10 is a bottom plan view of the blender jar of FIG. 1.
The broken lines depict portions of the article that form no
part of the claimed design.

1 Claim, 10 Drawing Sheets

Related U.S. Application Data

a continuation of application No. 29/718,727, filed on Dec. 27, 2019, now Pat. No. Des. 920,045.
